WASTE CLEANER MECHANISM

Kenneth E. Amick and Joseph S. Combs,
Indianapolis, Ind.

Application January 11, 1933. Serial No. 651,128

6 Claims. (Cl. 141—5)

This invention relates to the art of machines adapted for use in reclaiming used journal box waste and refers particularly to a structure employed to raise and lower and reciprocate a set of fingers for the purpose of agitating waste in a bath of hot oil as well as to intermittently move that waste from one end to the other of that bath.

The structure is so designed that a set of fingers may be reciprocated fore and aft in a tank adapted to hold heated oil so as to give the waste therein a like reciprocatory motion so as to thoroughly flush the waste with the oil. Further, the structure is designed to remove the fingers from engagement with the waste in a relative forward position and then carry the fingers back to a rear position to reengage with the waste and then again continue the reciprocatory motion to the end that the waste is gradually worked from the rear end of the bath to the forward end by disengagement and reengagement of the fingers in relatively spaced apart positions.

It is an object of our invention to provide a very simple timing mechanism to bring about the above indicated results without the use of chains. A further important object of the invention is to confine the timing and driving mechanism to within a compact space adjacent the tank within which the waste is operated upon.

These and other objects will become apparent in the following description of the invention as illustrated more or less diagrammatically in the accompanying drawings, in which

Fig. 1 is a fragmentary side elevation of a structure embodying our invention;

Fig. 2, a fragmentary top plan view;

Fig. 3, a reverse side elevation;

Fig. 4, a detail in side elevation of the shifting cam;

Fig. 5, an end elevation in detail of the cam and its immediate driving connection, and

Fig. 6, a further detail in fragmentary top plan view of the timing mechanism.

Like characters of reference indicate like parts throughout the several views in the drawings.

We employ a tank 10 adapted to hold a considerable volume of lubricating oil preferably in a heated condition. Within this tank we mount a horizontally disposed screen 11 on which waste is received and supported. This screen 11 is here shown as being longitudinally slotted so as to receive therethrough from the under side a plurality of vertically disposed fingers 12. These fingers are fixed to a frame 13 carried below the screen 11. A pair of spaced apart shafts 14 and 15 are rotatably mounted transversely of the tank 10 in

spaced relation below the screen 11 and each has fixed thereto the cam blocks 16 and 17 respectively. The frame 13 rests upon these cam blocks 16 and 17 and the blocks are so formed that upon simultaneous rotation of the shafts 14 and 15, the frame 13 and its fingers 12 will be raised and lowered accordingly. Each of these blocks is here shown as being substantially rectangular in shape with one end curved around from one side to the other whereby upon rocking the block, the frame may ride down over this curved portion on to a straight portion as indicated in Fig. 1 from the solid line position to the dash line position. That is, the difference in the elevation of the frame 13 from the raised to the lowered position is produced by revolving the blocks around from their upper longitudinally disposed positions to horizontally disposed positions, the blocks being longer than they are wide.

Both shafts 14 and 15 extend through the side walls of the tank 10 and have the bell cranks 18 and 19 fitted thereto respectively on the same side of the tank. A slide bar 20 is carried slidably by the brackets 21 and 22 in a horizontally disposed position above the cranks and a lower slide bar 23 is slidably carried by the brackets 24 and 25 in parallel arrangement with the upper bar 20 but spaced an equal distance below the shafts. These cranks 18 and 19 are fixed to the shafts 14 and 15 in respect to the cams 16 and 17 so that when the cams are turned to their upper positions to hold the frame 13 upwardly, the arms of the cranks are disposed symmetrically to each have an arm turned horizontally and forwardly and the other arm vertically downwardly. From the horizontally disposed arms of these cranks extend the links 26 and 27 respectively to pivotally engage with downturned arms carried by the bar 20. Also from each of the downturned arms of the cranks is a link 28 pivotally interconnecting it with an upturned arm carried by the slide bar 23, the links 28 being carried horizontally to the rear in parallel arrangement with the bar 23 while the other links 26 and 27 are carried vertically upwardly toward the other bar.

A shifting arm 29 is pivotally mounted on a bracket 30 midway between the upper and lower bars 20 and 23 and interengages these bars by pins 31 and 32 extending through slots in the respective ends of the arm.

A pair of vertically disposed guides 33 and 34 are mounted by their upper ends on the bar 20 to be held in fixed relation thereto and to hang downwardly therefrom parallel one with the other, the guides being here shown as being

secured to the rear side of the bar 20 to hang downwardly back of the bar 23 without connection in any way therewith. A cam 35 is provided to have a circular periphery of a diameter permitting it to be slidably fitted and carried between the two guides 33 and 34. This cam is connected to an arm 36 by a pin 37 located eccentrically of the center of the cam and the upper end of the arm 36 is fixed to a sleeve 38 5 rotatably carried on the end of a transverse shaft 39, the shaft 39 extending entirely across through the tank 10. An arcuate slot 40 is provided in the cam 35 to have its center of curvature at the center of the pin 37 and a pin 41 10 carried in a fixed position on the arm 36 slidably extends within this slot as a stop limiting the rotation of the cam thereby about the pin 37.

Power from some source (not shown) is transmitted to a spur gear 42 mounted on a transverse shaft 43 which incidentally drives an unloading conveyor 44'. This gear 42 is here shown, Fig. 2, as driving an idler gear 50, a second idler gear 51 loosely mounted on the shaft 14, and finally the shaft 39 through another gear 44 which is 20 fixed on the shaft 45 which extends transversely across the tank to carry a mutilated gear 46 on its outer end back of the guides 33 and 34. On the shaft 39 is mounted an eccentric 47 from which leads a shaft 48 to have its rear end 25 pivotally connected with the frame 13 whereby rotation of the shaft 39 will cause fore and aft reciprocation of the frame 13. The gear 46 is fixed to the shaft 45 in a position such that the teeth thereon will be brought around into mesh 30 with the teeth of the spur gear 49 which is fixed to the sleeve 38. This spur gear 49 is here shown, Fig. 6, as being in two sections, one being an integral part of the sleeve 38 and the other being fixed or keyed to the shaft 39.

40 In operation, the train of gears turning with the gear 42 is set in motion to have the fingers 12 reciprocate fore and aft as the frame 13 is shifted over the cam blocks 16 and 17 by the shaft 48. Beginning the sequence of operations, 45 for example, with the fingers 12 in the upper positions as indicated in Fig. 1, these fingers will be given an initial fore and aft reciprocation while in the upper positions. This reciprocation in the upper positions will continue as long as 50 that part of the gear 46 having no teeth thereon is traveling past the gear 49, but since the gear 46 is being continually driven by the shaft 45, the teeth on this gear will eventually come around to mesh with the gear 49 to cause rotation of 55 the gear 49. When this gear 49 revolves, that is that part of the gear fixed to the sleeve 38, then the arm 36 will be swung around to carry the cam wheel 35 against the rear guide 34 so as to shift the slide bar 20 to the rear, this movement of the bar 20 pulling the links 26 and 27 along therewith so as to tend to rock the shafts 14 and 15 to likewise rock the cam blocks 16 and 17 on each of the shafts from their upper 60 to their lower positions. Since the lower bar 23 is connected through the links 28 and the bell cranks 18 and 19 with the shafts 14 and 15, the slide bar 23 will tend to be shifted toward the front and this tendency is further emphasized by means of the rocker arm 29 interconnecting 65 the two bars. Thus by means of the two bars 20 and 23 and the interconnecting members, both shafts 14 and 15 will be simultaneously rocked a like distance. By reason of the peculiar hook-up between these two bars 20 and 23, the 70 shafts 14 and 15 are effectively retained at either

end of their permissible travel against accidental shifting since the links between the bars and the bell cranks come around to right angular positions to form braces requiring an application of power to displace them.

80 Following the rotation of the gear 49 to thus lower the fingers 12 as above indicated, the gear 46 continues in its travel leaving the fingers in their lower positions although they continue to reciprocate fore and aft but out of contact with the waste on the screen 11. The waste is thus allowed to soak for a time interval and the position of the eccentric 47 on the shaft 49 is so arranged in relation to the location of the teeth on the gear 46 that when the teeth again come around into contact with the gear 49 to return the cam blocks 16 and 17 to their upper positions, the fingers will return into the waste at a position rearwardly of that from which they were withdrawn when the cam blocks were lowered. The following reciprocation will then of course move the waste ahead a distance equal to the spacing longitudinally between the fingers 12.

85 Referring again to the gear 49 and its companion part which is fixed to the shaft 39, the gear is thus split in order to provide an additional drive to the shaft 39 through the shaft 45 and gear 46 while the arm 36 is being revolved to shift the frame 13. That is, while the gear 49 is being revolved to turn the arm 36, the shaft 39 is then being turned by the gear 49 and the gear 46.

90 While we have here shown and described our invention in the form now best known to us, it is obvious that structural changes may be made without departing from the spirit of the invention and we therefore do not desire to be limited to that precise form beyond the limitations as may be imposed by the following claims.

95 110 We claim:

1. In a journal box waste reclaiming machine, a tank, a screen within the tank adapted to support waste, a plurality of fingers, a frame carrying said fingers, a pair of shafts journaled transversely of the tank, cam blocks fixed to said shafts, said frame being supported by said blocks, said blocks being shaped to raise and lower the frame upon rotation of the shafts whereby said fingers are moved toward and away from said screen, a slide bar mounted to slide longitudinally of the tank, a crank on each of said shafts, a link interconnecting each of the cranks with said bar, guide means carried by the slide bar, a cam juxtaposed with said guide means, an arm pivoted to the cam, means for reciprocating said frame fore and aft, a train of gears actuating said reciprocating means, said train including a mutilated gear intermittently meshing by its teeth with a gear connected with said arm whereby said arm is swung to shift said cam to move said bar and rotate said shafts to in turn rock said blocks to raise and lower said frame in timed sequence with its fore and aft reciprocation.

120 125 130 135 140 145 150 2. In a journal box waste reclaiming machine, a tank, a screen within the tank adapted to support waste, a plurality of fingers, a frame carrying said fingers, a pair of shafts journaled transversely of the tank, cam blocks fixed to said shafts, said frame being supported by said blocks, said blocks being shaped to raise and lower the frame upon rotation of the shafts whereby said fingers are moved toward and away from said screen, a slide bar mounted to slide longitudinally of the tank, a crank on each of said shafts, a link

- interconnecting each of the cranks with said bar, guide means carried by the slide bar, a cam juxtaposed with said guide means, an arm pivoted to the cam, means for reciprocating said frame fore and aft, a train of gears actuating said reciprocating means, said train including a mutilated gear intermittently meshing by its teeth with a gear connected with said arm whereby said arm is swung to shift said cam to move said bar and rotate said shafts to in turn rock said blocks to raise and lower said frame in timed sequence with its fore and aft reciprocation, and means resisting reverse rotation of said shafts. 5
3. In a journal box waste reclaiming machine, a tank, a screen within the tank adapted to support waste, a plurality of fingers, a frame carrying said fingers, a pair of shafts journaled transversely of the tank, cam blocks fixed to said shafts, said frame being supported by said blocks, 10 said blocks being shaped to raise and lower the frame upon rotation of the shafts whereby said fingers are moved toward and away from said screen, a slide bar mounted to slide longitudinally of the tank, a crank on each of said shafts, a link interconnecting each of the cranks with said bar, guide means carried by the slide bar, a cam juxtaposed with said guide means, an arm pivoted to the cam, means for reciprocating said frame fore and aft, a train of gears actuating said reciprocating means, said train including a mutilated gear intermittently meshing by its teeth with a gear connected with said arm whereby said arm is swung to shift said cam to move said bar and rotate said shafts to in turn rock said blocks to raise and lower said frame in timed sequence with its fore and aft reciprocation, and means resisting reverse rotation of said shafts. 15
4. In a journal box waste reclaiming machine, a tank, a screen in the tank, a frame carrying a plurality of fingers, cam blocks supporting the frame and having symmetrical contours adapted to raise and lower the frame upon being rotated, transverse shafts carrying said blocks, a slide bar, means interconnecting said shafts and said bar whereby reciprocation of the bar will cause rotation of the shafts, means for reciprocating said frame fore and aft, means for shifting said slide bar, and timing means for operating said shifting means in timed sequence with said reciprocating means. 20
5. In a journal box waste reclaiming machine, a tank, a screen in the tank, a frame carrying a plurality of fingers, cam blocks supporting the frame and having symmetrical contours adapted to raise and lower the frame upon being rotated, transverse shafts carrying said blocks, a slide bar, means interconnecting said shafts and said bar whereby reciprocation of the bar will cause rotation of the shafts, means for reciprocating said frame fore and aft, means for shifting said slide bar, and timing means for operating said shifting means in timed sequence with said reciprocating means, said timing means comprising a mutilated gear constantly driven in relation to said reciprocating means, and a spur gear adapted to mesh with the teeth on the mutilated gear, the spur gear being connected with said shifting means. 25
6. In a journal box waste reclaiming machine, a tank, a screen in the tank, a frame carrying a plurality of fingers, cam blocks supporting the frame and having symmetrical contours adapted to raise and lower the frame upon being rotated, transverse shafts carrying said blocks, a slide bar, means interconnecting said shafts and said bar whereby reciprocation of the bar will cause rotation of the shafts, means for reciprocating said frame fore and aft, means for shifting said slide bar, and timing means for operating said shifting means in timed sequence with said reciprocating means, and means normally retaining said slide bar at either end of travel and assisting rotation of said shafts during shifting of the bar. 30
